(21) Appl. No.: **29/699,164**

(57) **CLAIM**

(22) Filed: **Jul. 23, 2019**

The ornamental design for a modular fin with common rail system, as shown and described.

(51) LOC (13) Cl. **21-02**

DESCRIPTION

(52) U.S. Cl.

USPC **D21/806**

(58) **Field of Classification Search**

USPC D21/806, 807
CPC A63B 31/00; A63B 31/02; A63B 31/08;

A63B 31/10; A63B 31/11

See application file for complete search history.

FIG. 1 is a perspective view of a connector rail system of a modular fin;

FIG. 2 is a top view thereof;

FIG. 3 is a bottom view thereof;

FIG. 4 is a right side elevation view thereof;

FIG. 5 is a left side elevation view thereof;

FIG. 6 is a perspective exploded view thereof; and,

FIG. 7 is a top exploded view thereof.

The broken lines depicting the portions of the swim fin are for illustrative purposes and do not form part of the claimed design.
